UNITED STATES PATENT OFFICE.

SEVERIANNO ANTONIO DE CASTILHO, OF NEWCASTLE-ON-TYNE, ENGLAND.

FIRE-ESCAPE.

SPECIFICATION forming part of Letters Patent No. 451,852, dated May 5, 1891.

Application filed December 11, 1890. Serial No. 374,391. (No model.) Patented in England May 30, 1890, No. 8,363.

To all whom it may concern:

Be it known that I, SEVERIANNO ANTONIO DE CASTILHO, Brazilian naval officer of the Republic of the United States of Brazil, residing in Newcastle-on-Tyne, Northumberland county, England, have invented certain Improvements in Fire-Escapes, (for which I have obtained a British Patent, No. 8,363; dated May 30, 1890,) of which the following is a specification.

My invention relates to improvements in fire-escapes and apparatus therefor, and has for its object the provision of a simple and efficient mode of escape from the several floors of any building on fire.

I will describe my invention with reference to the accompanying drawings, in which—

Figure 1 shows a side view of the complete apparatus; Fig. 2, an end vertical section of the pulley and brake device thereof, and Fig. 3 an enlarged explanatory sectional view of part of the same brake device.

Like letters or marks of reference designate like parts.

Referring to the figures, the drum or pulley n is shown mounted on an axle n' , secured in a bracket n^2 , bolted to the jib-frame n^3 , fixed in a socket n^4 , bolted to the window-sill n^5 .

n^6 is the rope or cable, the movements of which are governed by a frictional brake n^7 , attached to the pulley n . This brake consists of alternate layers (see Fig. 3) of light circular steel plates n^8 , carried by the drum-spindle n' , and brass plates n^9 , carried by the drum and acted upon by a disk-spring m , the compression of which is governed by a nut

m' and handle m^2 on the spindle. To the spindle is also fixed a ratchet-wheel m^3 , engaging a pawl m^4 on the bracket n^2 . When lowering, the spindle n' and handles m^5 and m^2 are held from revolving by means of the pawl, and consequently the weight will only lower by overcoming the friction of the brake, and if the friction be too little it can be increased by screwing up the nut m' by means of the handle m^2 . To lift the rope again the crank-handle m^5 is turned, and it, being fixed to the spindle, will revolve the drum, provided the weight to lift be not greater than the friction at which the brake is set. Should it be desired at any time to lower the rope without any weight attached, the crank-handle m^5 should be revolved in the direction of lowering, while the pawl m^4 is held clear of the ratchet-wheel by the trigger m^6 of the pawl.

What I claim as my invention, and desire to secure by Letters Patent, is—

The combination, with the jib-frame n^3 , of the bracket n^2 on the jib-frame, the drum n , the spindle n' , the brake-plates $n^8 n^9$, the disk-spring m , the handle m^2 , the nut m' , the ratchet-wheel m^3 , and the pawl m^4 , all arranged and acting together substantially as described.

In testimony whereof I have signed my name to this specification in the presence of two subscribing witnesses.

S. A. DE CASTILHO.
